FIG.1

FIG.3

FIG.2

FIG.4

FIGURE 1 is a plan view of the height gauge showing my new design;

FIGURE 2 is a front elevational view thereof;

FIGURE 3 is a rear elevational view thereof; and

FIGURE 4 is a side elevational view thereof.

The undisclosed side of the height gauge is essentially the same in appearance as the side shown, except for the handle and disc part.

I claim:

The ornamental design for a height gauge, substantially as shown and described.
